THE NORRIS PETERS CO., PHOTO-LITHO., WASHINGTON, D. C.

UNITED STATES PATENT OFFICE.

CLARENCE L. PARKER, OF LOS ANGELES, CALIFORNIA, ASSIGNOR OF ONE-HALF TO IRWIN W. ROSS, OF SAN FRANCISCO, CALIFORNIA.

PUMP.

SPECIFICATION forming part of Letters Patent No. 669,589, dated March 12, 1901.

Application filed April 19, 1900. Serial No. 13,522. (No model.)

To all whom it may concern:

Be it known that I, CLARENCE L. PARKER, a citizen of the United States, with post-office address and residence at 643 North Main street, city of Los Angeles, in the county of Los Angeles and State of California, have invented certain new and useful Improvements in Pumps, of which the following is a full, clear, and exact description, reference being had to the accompanying drawings, which form a part of this specification.

My invention relates to certain new and useful improvements in pumps intended more especially for pumping crude oil, but which may be used generally for pumping liquids; and I do not desire to confine myself to its use as an "oil-pump," but for the purpose of brevity and convenience will refer to that term in the specification; and my invention consists in certain features of novelty hereinafter described and claimed.

In another application, Serial No. 15,357, filed May 3, 1900, I have shown, described, and claimed another improvement in pumps.

Figure I represents a longitudinal section of my improved pump, showing the pump-tubing and the principal operating parts of my invention. Fig. II is a side elevation, the pump-tubing being omitted. Fig. III is a longitudinal section showing different positions of some of the operating parts from that shown in Fig. I. Fig. IV is a transverse section taken on line IV IV, Fig. III. Fig. V is a detail side elevation showing means for normally retaining the valve-cage within the pump-tubing. Fig. VI is a side elevation of the cage-valve and sectional clamp. Fig. VII is a transverse section taken on line VII VII, Fig. III. Fig. VIII is a transverse section taken on line VIII VIII, Fig. III.

Referring to the drawings, 1, 2, and 3 represent, respectively, the top, intermediate, and bottom sections of the pump-tubing.

4 represents a solid sectional pump-rod which operates vertically within the pump-tubing.

5 represents a plunger-barrel having its upper end secured to the lower end of the top section 1 of the pump-tubing by means of a threaded collar 6. The lower end of the plunger-barrel is connected with the upper end of the intermediate section 2 of the pump-tubing by means of a threaded collar 7. The

lower end of the intermediate section 2 is screw-threaded into the upper end of a sleeve 8, as shown at 9, the lower end of said sleeve being in turn secured at 10 to the upper end of the bottom section 3 of the pump-tubing, said bottom section 3 being provided with a series of perforations 11, which permit the oil to flow into the interior of the pump-tubing.

12 represents a valve-cage which is adapted to be secured normally near the bottom of the pump-tubing, but which it is necessary to withdraw from the pump-tubing from time to time, said valve-cage having an upper collar 13, surrounding the pump-rod 4, to permit said pump-rod to operate freely when raising or lowering the valve-cage.

14 represents pendent legs extending downwardly from the upper collar 13 within the pump-tubing, the lower ends of the said legs being screw-threaded at 15 into a lower collar 16.

17 represents pendent levers pivoted at 18 to the sleeve 8.

19 represents dogs having upper and lower beveled inner faces 20 21, respectively, said dogs resting normally within slots 22 in the sleeve 8 and being held there by means of springs 23, which press against the outer faces of said dogs and which permit them to be forced backward when occasion requires, as shown in dotted lines, Fig. I.

24 represents the cage-valve, said cage-valve surrounding the pump-rod 4 and being formed of a half-sphere, with its convex side projecting downwardly. Said cage-valve is adjustably secured to the pump-rod by means of a sectional clamp 25, which embraces the pump-rod and which is adjustably secured thereto by means of springs 26, each having arms 27, which embrace the sectional clamp.

28 represents studs on the upper side of the cage-valve 24, and 29 represents links having their lower ends pivoted at 30 to the studs and their upper ends pivoted at 31 to the sectional clamp 25. The object of the sectional clamp is to compensate for wear of the pump-rod, said sectional clamp constantly pressing inwardly and having a pivotal connection with the cage-valve 24. The cage-valve will not tend to hold the lower ends of the sectional clamp away from the pump-rod.

32 represents catches pivoted at 33 to the

pendent levers 17. The office of the said catches is to engage at their inner ends the angular annular notch 34 in the collar 16, which forms the bottom of the valve-cage.

5 35 represents an upper collar secured to the pump-rod. Beneath the upper collar 35 and within the perforated bottom section 3 of the pump-tubing 1 loosely mount on the pump-rod 4 an agitator-ring 36, having a lower sec-

10 tion 38, said agitator-ring serving the purpose of stirring up the oil and sand, so as to facilitate its passage upwardly through the pump-tubing, and being limited in its upward movement by the upper collar 35.

15 37 represents a stop, also on the pump-rod 4, adapted to limit the downward movement of the agitator-ring 36. The agitator-ring 36 does not move with the positive action of the pump-rod 4 until either the upper collar 35

20 comes in contact with its upper side or the stop 37 comes in contact with its underside, this variable motion serving to facilitate the churning up or the agitating of the oil and the foreign substances contained therein. When it

25 is desired to withdraw the valve-cage 12 for cleaning or other purposes, the pump-rod is raised until the agitator-ring 36 comes in contact with the beveled inner faces 21 on the dogs 19, and said dogs being pressed outwardly

30 withdraw the catches 32 from the angular annular notch 34 in the valve-cage, which frees the valve-cage and permits it to pass upwardly with the rod.

35 39 represents a ring resting upon the upper end of the collar 16, said ring serving as a seat for the cage-valve 24. The cage-valve 24, while not having a positive movement, as before described, facilitates the pumping of the oil over the action of a valve that is not in

40 any manner raised or lowered by the operation of the pump-rod.

45 40 represents a plunger for pumping the oil, having a collar 41 secured to its lower end, said collar serving as a seat for an upper

50 valve 42, having an annular shoulder 43, which seats against the collar 41. The pump-rod 4 is formed in sections, said sections being connected to each other by being screw-threaded into the upper valve 42 and lower

55 stop 37, as shown at 44, said lower valve and stop thus serving as a coupling for sections of the pump-rod. The plunger 40 is raised by the upper valve 42 coming in contact with its lower end as the pump-rod is raised, and

60 the plunger is depressed by means of a plunger-bracket 45, which comes in contact with the upper end of the plunger 40, the plunger-bracket 45 also serving as a coupling between two sections of the pump-rod, there being a

65 screw-threaded hub 46 for said purpose. The position of the plunger-bracket on the upper valve and cage-valve on the upper stroke of the pump-rod before the plunger is raised is shown in Fig. I, while in Fig. III is represented the position assumed by the rod, with

the plunger-bracket, upper valve, and cage-

valve, when the pump-rod is in its lowest position. The lowest position of the agitator-ring 36 is shown in Fig. I and its upper position in Fig. III. The position of the agitator-ring 36, lower stop 37, and pendent dogs 19 when the operating parts are being withdrawn between the dogs is shown in dotted lines in Fig. I.

I claim as my invention—

1. In a device of the kind described, the combination of the pump-rod, the tubing, a cage normally secured to the tubing and a valve within the cage having frictional contact with the pump-rod, substantially as set forth.

2. In a device of the kind described, the combination of the tubing, a cage placed within the tubing and normally secured thereto, a pump-rod, a valve adapted to slide on the pump-rod and spring-clamps for supporting said valve, substantially as set forth.

3. In a device of the kind described, the combination of the tubing, a cage within the tubing and normally secured thereto, a pump-rod, a valve adapted to operate on the pump-rod, friction-clamps for supporting the valve and a link connection between said clamps and valve, substantially as set forth.

4. In a device of the kind described, the combination of the tubing, a sleeve secured to the tubing, levers pivoted to the sleeve, dogs on the levers having cam-faces, a cage having an annular notch and catches on the levers adapted to normally engage in said annular notch, substantially as set forth.

5. In a pump the combination of the tubing, a pump-rod, a standing valve, a housing for inclosing said valve, a valve-stop, catches in connection with the housing for normally holding the valve-stop, and arms pivoted to said catches whereby outward pressure upon the same will release said valve-stop, substantially as set forth.

6. In a device of the kind described, the combination of the tubing, a sleeve secured to the tubing, a cage within the tubing having an annular notch, levers pivoted to the sleeve, catches for engaging the annular notch, cam-faced dogs on the levers, springs for normally holding the dogs in a closed position and means for opening said dogs and catches and releasing the cage, substantially as set forth.

7. In a device of the kind described, the combination of the tubing having perforations, the pump-rod, an agitating-ring loosely mounted on the pump-rod, a collar for depressing said ring, and a stop beneath the ring which is adapted to come in contact therewith and raise said ring, substantially as set forth.

CLARENCE L. PARKER.
